United States Patent Office.

EVAN SKELLY, OF PLAQUEMINE, LOUISIANA.

Letters Patent No. 96,155, dated October 26, 1869.

IMPROVED MACHINE FOR BLEACHING CANE-JUICE.

The Schedule referred to in these Letters Patent and making part of the same.

To all whom it may concern:

Be it known that I, EVAN SKELLY, of Plaquemine, in the parish of Iberville, and State of Louisiana, have invented a new and improved Machine for Bleaching Cane-Juice; and I do hereby declare that the following is a full, clear, and exact description thereof, which will enable others skilled in the art to make and use the same, reference being had to the accompanying drawings, forming part of this specification.

This invention relates to improvements in machines for defecating and bleaching cane-juice by the use of sulphurous-acid gas, and for manufacturing the said gas, and cooling the same, previous to the application to the juice.

The invention comprises an improved arrangement of automatic feeding and air-supplying apparatus for the furnaces, having an improved means for varying their capacity; also, an improved arrangement of cooling-devices, through which the gas is passed and cooled in the presence of water; also, an arrangement of means for agitating the juice, and exhausting the air, and delivering the gas thereto, in a manner to produce the most intimate contact of the gas with the particles of juice for bleaching.

Figure 1 represents a plan view, partly sectioned.

Figure 2 represents a side view, partly sectioned.

Figure 3 represents a section on the line $x-x$ of fig. 1.

Figure 4 represents a sectional elevation of a modified arrangement of cooling-apparatus.

Figure 5 represents a sectional elevation of another modification of the same.

Figure 6 represents a plan view of fig. 4, partly broken.

Similar letters of reference indicate corresponding parts.

A represents the furnace for generating the gas, and B, a pan therein, for containing the sulphur.

The furnace is intended to be provided with one or more pans, according to the quantity of gas required, which is best regulated by the superficial area of the burning-surface, the depth of the supply having but little influence on the quantity produced.

C represents the air-supply passage, having a valve, D, to be worked to regulate the supply of air, as will be presently shown.

The end of the passage C is provided with a sliding gate, E, also for regulating the supply.

F represents another gate, opening into the said passage C, for cleaning it.

G is a pendent plate, to cause the air to pass down upon the burning sulphur.

H is a feeding-hopper, placed upon the top of the furnace, and provided with a revolving recessed valve,

I, at the bottom, which is rotated slowly and intermittently, and delivers the sulphur in measured quantities, closing the passage from the said hopper to the furnace at each time of delivering.

This valve is on the end of a shaft, K, having a ratchet-wheel, L, pawl M, and lever N, worked by a connecting-rod, O, from the main driving-shaft P.

The connection of the rod O with the lever N is arranged to be adjusted for varying the throw of the lever N and ratchet, and thereby varying the speed of the wheel L and valve.

Q represents the cooling-chamber, into which the gas is discharged from the furnace through the pipe A, which discharges the gas on to the surface of water therein, supplied through the funnel S and V-shaped pipe T, passing down to or near the bottom of the chamber, and up to or about the top of the water, forming a trap to prevent the escape of the gas through the funnel.

U is an escape-pipe for the surplus water, leading from the bottom; also, to prevent the escape of gas.

From this chamber the gas is conveyed through a pipe, V, to the hollow axle W of a gas-distributing wheel, X, working in a closed trough, Y, through which the cane-juice is passed, for the purpose of bleaching.

This wheel is provided with four (more or less) broad, hollow, curved arms Z, open at the ends, and having perforations at α , in the front sides, or the sides which beat against the juice, as the wheel revolves, to beat the juice into spray, and, at the same time, to exhaust the air like a fan, and to distribute the gas in the said spray, whereby the juice is bleached to the best advantage, and the air separated and driven off.

The juice flows in and through the trough, as indicated by the arrow.

A¹ represents a perforated plate, in the elevated part of the trough, above the wheel, for arresting the spray thrown up by the wheel, and for allowing the air to separate and pass off through the passage B¹.

C¹ represents pendent partitions, at each end of the trough, to prevent the escape of gas.

E¹ represents float-valves, for the same purpose.

F¹ represents a pendent valve behind the wheel, and arranged to be turned on its axis by the juice thrown against it by the wheel.

This valve is designed to actuate the air-valve D in the passage C. The axles of both are therefore provided with cranks F² D², and connected by a rod, G¹.

The valve F¹ will be moved, more or less, according to the quantity of juice thrown against it, and this will depend upon the quantity passing through; and the quantity of gas required is in proportion to the

juice passing; therefore, with the greater quantity, the valve D is opened more, and more air admitted, and more gas produced.

In the modified arrangement of cooling-apparatus, represented in figs. 4, 5, and 6, I have represented tubes, or other conductors, for conveying the gas from the furnace down under the water, and to be partly surrounded by the water, instead of discharging the said gas directly above the water.

A^2 represents a broad flat conductor, receiving the gas at a^2 , and conveying it down through the part a^3 , and up through a^4 to the tubes a^5 .

A^3 , fig. 6, represents tubes, similarly arranged.

Other similar arrangement of the cooling-apparatus may be employed.

Having thus described my invention,

I claim as new, and desire to secure by Letters Patent—

1. Combination, with the furnace A, of the air-conductor C, valve D, arranged for operating to vary the supply, the hopper H, and revolving recessed feeding-valve I, all substantially as specified.

2. The combination, with the furnace A, and the distributing-wheel and trough, of a gas-cooler, arranged substantially as specified.

3. The combination, with a closed agitating-trough arranged for passing the liquid through it, of a revolving agitating-wheel, arranged for receiving the gas from a furnace, or over or through water, and for exhausting the air from the said agitating-chamber, and delivering the gas to the liquid therein, substantially as specified.

4. The combination, with the trough, of the pendant plates C¹, and float-valves E¹, substantially as specified.

5. The combination, with the air-valves D, of the valve F¹, when connected and arranged substantially as described.

6. The combination, with the agitating-trough and wheel X, of the perforated plate A¹, substantially as specified.

7. The mode of increasing or diminishing the capacity or area of the burning-surface, by the employment, in combination with the said furnace, of pans B, in which to burn the sulphur, substantially as specified.

EVAN SKELLY.
